UNITED STATES PATENT OFFICE.

JOHN J. MARTIN AND PATRICK CUNNINGHAM, OF PINOS ALTOS, TERRITORY OF NEW MEXICO.

ROCK-DRILL.

SPECIFICATION forming part of Letters Patent No. 437,609, dated September 30, 1890.

Application filed February 5, 1890. Serial No. 339,334. (No model.)

To all whom it may concern:

Be it known that we, JOHN J. MARTIN and PATRICK CUNNINGHAM, of Pinos Altos, in the county of Grant and Territory of New Mexico, 5 have invented a new and Improved Rock-Drill, of which the following is a full, clear, and exact description.

Our invention relates to improvements in rock-drills; and the object of our invention is to provide a drill that can be easily operated, that will work rapidly, that will be durable, and that will be especially adapted to hard rocks.

To this end our invention consists in a 15 drill having a rounded serrated end forming two downwardly-projecting lips, and having two oppositely-curved cutting-edges between said lips, as hereinafter fully described and claimed.

20 Reference is to be had to the accompanying drawings, forming a part of this specification, in which similar letters of reference indicate corresponding parts in all the figures.

Figure 1 is an inverted side elevation of 25 the drill embodying our invention, showing the serration in the end of the drill and the cutting-edges of the same; Fig. 2, an inverted side elevation, the view being taken at right angles to Fig. 1; Fig. 3, an end view showing 30 the faces of the drill and the cutting-edges thereon.

The drill A is provided with a serrated end, thus forming two lips B, which are curved slightly outward from the drill-shaft, and 35 which are rounded off at the ends, as shown in Fig. 2, so that they will present a round edge to the rock. The lips B are convexed on the inner face and meet in the center of the drill, and each lip is provided upon its 40 convex face with an inwardly-curved convex cutting-edge a, which extends from the edge of the lip nearly to the center of the drill.

The cutting-edges a of the lips B are curved in opposite directions, so that there will be a cutting-edge near each side of the drill. The 45 edges a are made slightly convex, and the faces of the lips B are beveled upon each side of the cutting-edges, so that the particles of rock broken by the drill will be forced away from said cutting-edges, leaving them constantly free to cut. The bevel from the inner end of the cutting-edges should be very sharp, as shown in the drawings, so that the 50 drill will be sure to clear itself.

The drill is operated in the usual manner, 55 being driven into the rock and turned slightly after each blow of the hammer upon it. The projecting ends of the lips B will first pierce the rock and then the cutting-edges a will cut toward the center. The shape of the drill 60 will enable it to be turned very easily in the drill-hole as the rounded ends will not stick, and the rounded lips B and cutting-edges a will cut very rapidly into the rock. It will be noticed that the edges a are of such shape 65 that they will not be easily dulled, and consequently the drill is very durable.

Having thus described our invention, what we claim as new, and desire to secure by Letters Patent, is—

As a new article of manufacture, a rock-drill provided with a serrated end forming lips having convex inner faces and rounded ends, and provided on their convex faces with inwardly and oppositely curved convex cutting-edges, extending from the edges of the lips to opposite sides of a line passing through the center of the drill, as set forth.

JOHN J. MARTIN.
PATRICK CUNNINGHAM.
